A. P. Lohmann
By his Attorney
Robert M. Peterson

UNITED STATES PATENT OFFICE.

ALFRED P. LOHmann, OF AKRON, OHIO, ASSIGNOR TO THE B. F. GOODRICH COMPANY,
OF NEW YORK, N. Y., A CORPORATION OF NEW YORK.

LADDER-FOOT.

1,276,666.

Specification of Letters Patent. Patented Aug. 20, 1918.

Application filed February 21, 1917. Serial No. 150,178.

To all whom it may concern:

Be it known that I, ALFRED P. LOHmann, a citizen of the United States, residing at Akron, in the county of Summit and State 5 of Ohio, have invented certain new and useful Improvements in Ladder-Feet, of which the following is a specification.

This invention relates generally to pivotally-jointed anti-slipping ladder feet, and 10 more specifically to those of the universal-joint type. Its object is to provide a device of greater durability and simplicity, and of less expensive construction, than those heretofore proposed.

15 Of the accompanying drawings,

Figure 1 is a perspective view of the lower portion of a ladder provided with feet embodying a preferred form of my invention.

20 Fig. 2 is a vertical section of one of the ladder feet and the ladder rail to which it is attached.

In the drawings, 10, 10 are the side rails and 11 is one of the rungs of a ladder. In 25 its preferred form, as shown, my improved ladder foot comprises, first, an attaching bracket consisting of a pair of flat metal bars or straps 12 adapted to embrace the lower end of the ladder rail and attached thereto by a pair of bolts 13 connecting the 30 two straps, said bars having on their lower ends two hemispheres 14, 14 forming a ball head; and secondly, a lower or tread section having a socket 15 formed between a pair of nesting cup-shaped plates 16, 17 together with a cup-shaped tread-member 18 composed of vulcanized soft-rubber compound, preferably reinforced with layers of 35 fabric 19.

The lower part of the socket is a hemispherical depression 20 formed in the middle 40 of the lower or inner cup-shaped plate 17 and supporting the ball head 14, 14, and the upper part of said socket is a spherical segment or flange 21 formed on the upper or 45 outer cup-shaped plate 16 and provided with an upper mouth or circular opening somewhat larger in diameter than the width of the bars 12. The two cup-shaped plates are 50 connected by suitable fasteners, such as rivets 22, and the rubber tread-member 17 is clamped between the two plates. The two bars 12, which are spread apart and parallel in their upper portions, converge down-

wardly to form a neck 23 just above the ball head 14, 14, where they are connected by a 55 rivet 24.

In assembling the parts of the ladder foot, the two bars 12, before being riveted together, are passed singly, upper end foremost, through the opening in the flange 21, 60 and are then connected by the rivets 24 so that their hemispheres 14 form the ball head and their upper portions assume the relation shown for receiving the ladder rail. Then the rubber tread-cup 18 is inserted within 65 the upper plate 16, the lower plate 17 is inserted within the tread-cup, and the two plates are riveted together, which makes the device complete and ready for use.

I claim:

1. A ladder foot comprising an attaching bracket provided with a head constituting a member of a pivotal joint, a pair of plates forming between them a complementary pivotal-joint member or socket embracing said 75 head, and an anti-slipping tread-member secured between said plates.

2. A ladder foot comprising a bracket adapted for attachment to the ladder rail and formed with a ball head, a pair of 80 plates forming a socket embracing said head, said ball and socket constituting a universal joint, and a rubber tread-member clamped between said plates.

3. A ladder foot comprising a pair of 85 nested cup-shaped plates secured together by fastening devices and forming the socket member of a ball-and-socket joint, a cup-shaped rubber tread-member clamped between said plates, and an attaching bracket 90 having a ball head occupying said socket.

4. A ladder foot comprising a tread section having upper and lower plates forming the socket member of a ball-and-socket joint, the upper plate having a circular opening to 95 said socket, an anti-slipping tread on said tread-section, and an attaching bracket comprising a pair of bars whose upper portions are adapted to embrace between them the ladder rail, said bars converging downwardly to a neck, and a pair of hemispheres forming a ball head in said socket and adapted to be assembled with the upper plate by passing said bars singly, upper ends foremost, through the opening in said upper 100 plate.

5. A ladder foot comprising a pair of nested cup-shaped plates forming a spherical socket member open at the top through the upper plate, an interposed cup-shaped rubber tread-member, fastening devices securing said plates together, and an attaching bracket comprising a pair of bars spread

apart at their upper ends, converging downwardly and joined together at a neck, and having hemispheres at their lower ends forming a ball head in said socket.

In testimony whereof I have hereunto set my hand this 19th day of February 1917.

ALFRED P. LOHmann.
